UNITED STATES PATENT OFFICE.

SAMUEL E. NUTTING, OF IRON RIDGE, WISCONSIN.

SEAL-LOCK.

SPECIFICATION forming part of Letters Patent No. 278,450, dated May 29, 1883.

Application filed January 20, 1883. (Model.)

To all whom it may concern:

Be it known that I, SAMUEL E. NUTTING, of Iron Ridge, in the county of Dodge and State of Wisconsin, have invented a new and 5 Improved Seal-Lock for Car-Doors, of which the following is a full, clear, and exact description.

The object of the invention is to combine certain parts in a seal-lock, as hereinafter described, and pointed out in the claim.

Reference is to be had to the accompanying drawings, forming part of this specification, in which similar letters of reference indicate corresponding parts in all the figures.

15 Figure 1 is a perspective view of a section out of the side of the car with my improved seal-lock applied. Fig. 2 is a section of Fig. 1 on the line xx , and Fig. 3 is a section of the seal and of the dies of the pliers used for sealing the lock.

I fit a metal cylinder, a , in the post b of the door-frame or other part of the side of the car to which the door c is to be locked, making it fast in any approved way, said cylinder 25 having an oval head, d , for receiving the end of the hasp e , which is suitably slotted to fit said head, the cylinder being also bored through its center lengthwise for receiving the locking-bolt f , which has a head, g , corresponding in form to head d , projecting beyond it, for the hasp e to pass over it onto head d . The bolt extends through cylinder a , and is secured 30 by pins h , which allow it to turn in said cylinder, but prevent it from being drawn out. The pin i , projecting from the inner end of cylinder a , limits the rotation of the locking-bolt to the two required positions of the head of the latter, and the hasp e , head d , and the bolt f have each a slot or hole, which coincide when head g is set for locking the hasp, for securing 35 said head in that position to lock the car by a thin metal strip, k , or a wire to be fastened by a seal-rivet, l , of soft metal, which is to be riveted, after passing through the strip, by 40 pliers m , having dies n , to be prepared with 45 the name or any characters to indicate the station where they are to be used, so that in case the seals are broken open the locality where it is done will be indicated.

The lock is simple to make and apply to the 50 car, and it will be found well calculated for durability.

I am aware that it is not new to make a tag or seal of brass, tin, or other soft metal; but

What I do claim as new and of my invention is—

The combination, in a seal-lock, of hollow and headed cylinder a , headed bolt f , slotted hasp e , and the seal k , the hasp, bolt, and cylinder-head having a slot or hole for the seal 60 strip or wire, substantially as described.

SAMUEL EDWARD NUTTING.
